US00D774034S

(12) **United States Design Patent** (10) Patent No.: **US D774,034 S**
Kheradpir et al. (45) Date of Patent: **** Dec. 13, 2016**

(54) **RAPID REGISTRATION SCANNER**
(71) Applicant: **SYNAPTIVE MEDICAL (BARBADOS) INC.**, Bridgetown (BB)
(72) Inventors: **Leila Kheradpir**, Toronto (CA); **Jakub Jankowski**, Toronto (CA); **Samson Ng**, Toronto (CA); **Kyle Richard Dupont**, Toronto (CA); **Omar Taqreiz Ahmad Khan**, Toronto (CA); **Kishan Hitesh Shah**, Toronto (CA); **Kirusha Srimohanarajah**, Toronto (CA)
(73) Assignee: **SYNAPTIVE MEDICAL (BARBADOS) INC.**, Bridgetown (BB)
(**) Term: **15 Years**
(21) Appl. No.: **29/534,585**
(22) Filed: **Jul. 30, 2015**
(51) LOC (10) Cl. **14-02**
(52) U.S. Cl. **D14/426**; D24/186

CLAIM

We claim the ornamental design for a rapid registration scanner, as shown and described.

DESCRIPTION

FIG. 1 is a left side elevation view of a rapid registration scanner;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side perspective view thereof; and,
FIG. 7 is a right side perspective view thereof.
